G. BERRY,
AIR DRAFT MOTOR,
APPLICATION FILED JUNE 3, 1920.

1,380,036.

Patented May 31, 1921.

UNITED STATES PATENT OFFICE.

GOLDEN BERRY, OF CHECOTAH, OKLAHOMA.

AIR-DRAFT MOTOR.

1,380,036.

Specification of Letters Patent. Patented May 31, 1921.

Application filed June 3, 1920. Serial No. 336,346.

To all whom it may concern:

Be it known that I, GOLDEN BERRY, a citizen of the United States, and a resident of Checotah, in the county of McIntosh and State of Oklahoma, have invented certain new and useful Improvements in Air-Draft Motors, of which the following is a specification.

My invention relates to improvements in air motors, and it consists in the constructions, combinations and arrangements herein described and claimed.

One of the foremost objects of my invention is to provide a portable air motor, which is of such construction that it can be carried about, being of very light weight, and set up wherever required, for the purposes of running toys, fans, ventilating rooms, etc.

20 A further object of the invention is to provide a draft motor with a relatively long draft tube or flue, arranged to be supported in any suitable manner and position while the device is in operation, but which can be 25 telescoped into the flue case so as to make the apparatus portable.

A further object of the invention is to provide simple but efficient means for securing the flue sections together.

30 A still further object of the invention is to provide a noiseless, frictionless and oil-less motor, capable of running without attention, in any position and at any time.

Other objects and advantages will appear 35 in the following specification, reference being had to the accompanying drawing, in which:—

Figure 1 is a perspective view of the flue case as it appears when in its portable condition,

40 Fig. 2 is a vertical section of the case, showing the draft tube or flue telescoped therein,

Fig. 3 is a side elevation showing the draft 45 tube extended and the motor in the operative position,

Fig. 4 is a detail enlarged section, showing the motor fitted in place inside of the flue case, when the device is in the operative 50 position, and

Fig. 5 is a detail sectional view, more specifically referred to below, illustrating how the flue sections are joined.

In carrying out my invention, I provide a

case 1, of heavy cardboard, sheet metal, or other suitable material, with an inner wall 2, a closed and rather heavy bottom 3 and a partition 4 adjacent to which the draft tube or flue 5 is secured, as clearly shown in Fig. 4. The upper end of the case 1 is open both at the space between the walls 1 and 2 and in the center.

The draft tube 5 is so made that when it is desired to pack the apparatus when not in use, it can be collapsed or telescoped into the space between the walls 1 and 2, as clearly shown in Fig. 2. This is one of the important features of the invention and lends directly toward the portability of the draft motor.

70 Paper or other similar material is employed in making the draft tube 5, which consists of major sections defined in Fig. 3 between the points marked 6. Intermediately of these points, the major sections are 75 strengthened by hoops 7 of wire, or other suitable material. The major sections are joined at the points 6, the joints comprising an inner band 8 on one of the sections, through which the points of a plurality of 80 pins 9 project in order that the edge of the companion section may be impaled thereon when fitted in place over the band.

An elastic ribbon 10 serves to keep the pins in place and to prevent the major sections from pulling apart. It is to be observed that the band 8 is reinforced by a 85 number of wire hoops 11 as shown in Fig. 5.

The motor, or active part of the apparatus, 90 comprises the propeller 12 on the shaft 13, which has needle or pointed ends 14, contacting the end bearings 15. The shaft is held in place by brackets 16 which form parts of the bearings.

95 A balance wheel 17 serves to equalize the motion of the shaft. Although this wheel is not so shown in the drawing, in actual practice is an open wheel so that the air can pass through the tube 18 in which the motor is housed, when in the operative position illustrated in Fig. 3. Any suitable type of pulley 19 may be fixed on the shaft 13 so that the power can be taken off by means of belt 20. A flange 21 on the tube 18 is engaged by the 100 securing means 22 to hold the motor in place in the inner case 2, when it is either in the operative or inoperative position. To free the motor tube 18, it is only necessary to 105

turn the securing means 22 a quarter revolution so as to open the passage for the flange 21.

The operation

5 may be briefly reviewed to advantage. Under ordinary conditions, that is to say, when the apparatus is collapsed and not in use, it appears very much as illustrated in 10 Fig. 1. The motor is turned around, as shown in Fig. 2, so that only the short end of the tube appears beyond the lower end of the outer case 1. Rings 23 on the case 1, are for the purpose of turning the apparatus up 15 until the draft tube 5 is withdrawn from the space between the inner and outer walls 2 and 1, and are thereafter employed in assisting to support the apparatus in the operative position.

20 After the draft tube 5 is fully drawn out, the upper end is suspended at any desired place, a collar 24 being provided for the purpose. The motor is reversed so that the long end of the tube 18 is exposed as in Fig. 25. It may be stated at this point that more power is gotten by adding sections to the draft tube so that a longer air conduit is provided.

The tube 5 and inner case 2 now constitute 30 an air conduit through which a stream of air passes from the bottom through the top. This moving stream of air causes the propeller 12 to rapidly revolve, consequently turning the pulley 19 and enabling the power 35 to be taken off for the purpose of running small toys, etc. The needle points of the motor shaft 13 require no lubrication, and being sharpened down to points, consequently cause but very little friction in running.

40 While the construction and arrangement of the improved air draft motor as herein described and claimed, is that of a generally preferred form, obviously modifications and 45 changes can be made without departing from the spirit of the invention or the scope of the claims.

I claim:—

1. An air-operated appliance, comprising 50 a case, an air motor reversible from an operative position for substantial concealment, and a draft tube collapsible into the case, to render the appliance compact and portable.

2. An air-operated appliance, comprising 55 a rigid case, a collapsible draft tube normally telescoped within the confines of the case but extensible to provide an air conduit, and an air motor normally substantially concealed within the confines of the case but 60 reversible to assume an operative position at the mouth of the air conduit in the case.

3. An air-operated appliance, comprising 65 a double-walled case providing a tube-space and air passage, a flexible draft tube secured

and normally collapsed in the tube space, 65 but extensible in continuation of the air passage to constitute an air conduit; and an air motor normally housed in the air passage when inoperative, but reversible at the mouth of said passage to assume the operative position.

4. The combination in an air-operated appliance, of an air tube, with a bottom collar; an air motor normally housed in the tube when inoperative, with a flange engaging the collar, but reversible in respect to the tube to an operative position, when the flange again engages the collar; and means carried by the collar for engaging the flange under both circumstances to secure the motor 80 in either position.

5. The combination in an air-operated appliance, of an air motor including a partially open tube, supporting a shaft with a propeller and pulley; and an air tube in the 85 end of which the open tube end, propeller and pulley are concealed when the motor is inoperative, but in respect to which the motor is reversible to expose the open tube end, propeller and pulley for operation.

90 6. The combination in an air-operated appliance, of a case including an outer wall and an air tube on the inside and spaced therefrom, with a collar providing a bottom in the space; an air motor including an open 95 tube, with journals and retaining means for the needle ends of a motor shaft, carrying a propeller, pulley and balance wheel; a flange near one end of the tube, contacting the collar when the motor is substantially 100 housed in the air tube in the inoperative position, and again contacting the collar when the motor is reversed to expose the aforesaid part in the operative position; and means carried by the collar for securing the 105 flange and motor in both positions.

7. The combination in an air-operated appliance, of a rigid double-tube case, defining a draft tube space and an air passage; and a draft tube secured at one end at the 110 bottom of the tube space, fitting around the inner tube and extensible in continuation of the air passage, consisting of a plurality of major sections of suitable reinforced flexible material, with means by which the sections are secured together, and a stiffening collar at the end of the uppermost section.

115 8. A draft motor, including a draft tube composed of a plurality of major sections of flexible material, one end of each section 120 embodying a stiffening band with reinforcing means, with a plurality of pins on the end of which the end of another section is impaled, and means encircling said structure keeping the section ends together when 125 joined.

GOLDEN BERRY.
